Primary Examiner — Robert M Spear*Assistant Examiner* — Ryan Harvey*(74) Attorney, Agent, or Firm* — Thomas M. Freiburger(57) **CLAIM**

The ornamental design for a two-sided high density bicycle rack, substantially as shown and described.

DESCRIPTION

FIG. 1 is a top plan view thereof;

FIG. 2 is a bottom plan view thereof;

FIG. 3 is a left side view thereof;

FIG. 4 is a right side view thereof;

FIG. 5 is a front elevation view thereof; and,

FIG. 6 is a back elevation view thereof.
